UNITED STATES PATENT OFFICE

HARVEY G. SENSENEY, JR., OF FLORENCE, SOUTH CAROLINA

PORTABLE ROAD SIGN

Application filed December 5, 1932. Serial No. 645,816.

My invention relates to a portable signal device.

When an automobile is wrecked, as when running off of the road, a wrecking car is called to pull the same out of the ditch, or the like, and return it to the road. This operation frequently requires the wrecking car to be positioned across the road. This work is frequently done on dark nights, and it not infrequently happens that another car is wrecked by driving into the wrecking car. Attempts have been made to overcome this difficulty by placing lanterns at suitable distances from the wrecking car, but these lanterns do not afford proper protection, as drivers mistake the same to indicate obstructions or holes in the roadway adjacent to the lanterns, and when passing the lanterns, do not appreciate the danger ahead. Some countries require that the wrecking crew carry two additional men to wave lanterns at suitable distances upon opposite sides of the wrecking car, but this is expensive.

In accordance with the present invention, I provide a portable signal device which may be carried in the wrecking car, and unloaded therefrom and positioned on the road at a suitable distance from the wrecking car. This signal device embodies an arm carrying a visual signal, and the arm is swung back and forth, simulating the swinging of the lantern by a man.

The device is so constructed that it is light, durable, cheap to manufacture, and readily portable. The driving means for the swinging arm is not only of simple construction, but serves to hold the swinging arm against perceptible swinging movements while the device is being transported.

In the accompanying drawing, forming a part of this specification, and in which like numerals are employed to designate like parts throughout the same,

Figure 1 is a front elevation of a signal device embodying my invention,

Figure 2 is a central vertical longitudinal section through the same, parts in elevation,

Figure 3 is a vertical section taken on line 3—3 of Figure 2, and,

Figure 4 is a horizontal section taken on line 4—4 of Figure 2.

In the drawing, wherein for the purpose of illustration is shown a preferred embodiment of my invention, the numeral 5 designates a base, which is preferably cylindrical, and this base has a vertical elongated preferably cylindrical casing 6, rigidly attached to the top of the same. The upper end of this casing is closed by a cover 7, rigidly attached thereto, and this cover is equipped with a handle 8, whereby the device may be conveniently carried.

The numeral 9 designates a transverse horizontal rock shaft, journalled through openings formed in the casing 6, and spacing sleeves 10 are mounted upon this rock shaft, within the casing 6.

The rock shaft 9 extends to the exterior of the casing 6, upon its forward portion, and a socket 11 is clamped thereto by a set screw 12, or the like, and this socket is rigidly attached to a swinging signal arm 12. This signal arm is provided at its upper end with a plate or disc 13, constituting a signal element and having the word "Stop" or the like, formed thereon. The letters constituting the word "Stop" are preferably coated with luminous paint, so that the same will be visible at night.

At its lower end, the arm 12 has an illuminated signal element 14, rigidly attached thereto. This illuminated signal element may be in the form of an oil lamp, or an electric lamp, and preferably embodies a red lens 15, for producing a red signal, visible at night. Upon the rear side of the lamp 14 I preferably provide a green lens 16. The invention is in no sense restricted to the precise colors employed, as both lenses may be red, or other colors used, as found advantageous.

Mounted within the base 5, is a spring motor 17, of any well known or preferred type. This spring motor is wound by a handle 18, extending to the exterior of the base 5. The spring motor embodies a vertical driving shaft 19, equipped with a vertical socket 20, polygonal in cross-section, for receiving the lower end of a vertical shaft section 21, such

lower end being also polygonal in cross-section. Arranged above and in alignment with the lower shaft section 21 is an upper vertical shaft section 22, which is adjustably connected with the shaft section 21, to be raised and lowered with relation thereto, by means of a sleeve 23, clamped to these shaft sections by set screws 24 and 25. The upper shaft section 22 is rotatable within a bearing 26, formed in a transverse bar 27, having a central flattened portion, and the ends of this bar are held within openings 28 formed in the casing 6, and may be spot-welded to the casing.

15 Mounted upon the upper end of the shaft section 21 is a horizontal eccentric or cam 29, having a hub 30, clamped to this shaft by a set screw 31, or the like. This horizontal rotating cam is positioned within a yoke or inverted U-shaped member 32, and the distance between the arms of this member is slightly greater than the diameter of the eccentric, affording a slight clearance. The yoke is provided centrally at its top with a 25 sleeve or hub 33, and this sleeve or hub is clamped to the rock shaft 9 by means of a set screw 34, or the like. The yoke is therefore rigidly attached to the rock shaft 9, for turning movement therewith, and also 30 coacts with the spacing sleeves 10, to prevent longitudinal movement of the shaft 9.

While I have shown and described the spring motor 17 as driving the shaft sections 21 and 22, yet the invention is not necessarily 35 restricted to the use of a spring motor, as an electric motor might be used where electricity is available, but it will ordinarily be preferred to use a spring motor.

40 The operation of the device is as follows:— The signal device is readily portable and may be carried by one man, engaging the handle 8. Two of these devices may be readily loaded into the wrecking car. When the location in the road is reached, the signal device is removed from the wrecking car, and is placed a suitable distance from the automobile, along the road. The spring motor 17 being wound up, and the lamp 15 being lit, the operator imparts to the signal arm 12, a 45 swinging movement, and the spring motor will then rotate the eccentric 29. This eccentric, rotating within the yoke, will rock the same back and forth, which rocking movement is imparted to the rock shaft 9, which will, in turn, oscillate the signal arm. Another driver approaching the signal device, will readily observe the swinging illuminated signal element 15, and thus be advised of the danger. In the day time, this signal 55 element 14 may or may not be illuminated, as desired, and the signal element 13 will then be visible. The signal element 14 is slightly heavier than the signal element 13, and this causes the yoke 32 to remain in contact, at one arm, with the eccentric 29.

It is to be understood that the form of my invention herewith shown and described, is to be taken as the preferred example of the same, and that various changes in the shape, size and arrangement of parts may be resorted to without departing from the spirit of the invention, or the scope of the subjoined claims.

Having thus fully described my invention, what I claim is:—

1. A portable signal device for use on roadways, comprising an upstanding casing having a base, a handle connected with the upper end of the casing, a transverse rock shaft carried by the casing, a motor mounted within the base, a longitudinal shaft extending through the casing and connected with the motor to be driven thereby, driving connecting means between the driving shaft and the rock shaft so that the rotation of the drive shaft is employed to rock the rock shaft, and a signal arm mounted upon the rock shaft to be oscillated thereby.

2. A portable signal device for use on roadways, comprising an upstanding support having a base, a transverse rock shaft carried by the upper portion of the support, a motor carried by the base, a drive shaft extending longitudinally of the support and driven by the motor, a horizontal eccentric element mounted upon the upper portion of the drive shaft, a vertical yoke carried by the rock shaft and receiving the eccentric element therein, and a signal arm mounted upon the rock shaft to be oscillated thereby.

3. A portable signal device for use on roadways, comprising an upstanding casing, a transverse rock shaft carried by the upper portion of the casing, a spring motor mounted in the lower portion of the casing, a drive shaft connected with the spring motor and extending longitudinally within the casing, a horizontal eccentric element carried by the upper portion of the drive shaft, a depending vertical yoke mounted upon the rock shaft and receiving the eccentric element therein, means whereby the elevation of the eccentric element may be varied with relation to the yoke, and a signal arm carried by the rock shaft to be oscillated thereby.

4. A portable signal device for use on roadways, comprising an upstanding casing, a longitudinal drive shaft arranged within the casing, a horizontal eccentric element mounted upon the drive shaft, a transverse rock shaft carried by the casing and arranged above the eccentric element, a yoke mounted upon the drive shaft and receiving the eccentric element therein, a signal arm mounted upon the rock shaft, and means to drive the rock shaft.

5. A portable signal device for use on roadways, comprising an upstanding casing provided in its sides with openings, a rock shaft extending through the openings, a yoke ar-

- ranged within the casing and clamped to the rock shaft, spacing sleeves mounted upon the rock shaft and arranged between the yoke and the casing, an eccentric element to oscillate the yoke, means to drive the eccentric element, and a signal arm mounted upon the rock shaft to be oscillated thereby.
- 5 6. A portable signal device for use on roadways, comprising an upstanding support having a base to be placed upon the roadway or the like and of sufficient area to prevent the ready tipping over of the support, a motor arranged adjacent to and carried by the base to increase the weight of the base, an oscillatory element mounted upon the upper portion 10 of the support, a signal element moved by the oscillatory element, and driving connecting means between the motor and oscillatory element.
- 15 7. A portable signal device for roadways, comprising an upstanding support, a spring motor mounted upon the support near its lower end, an oscillatory element mounted upon the support near its upper end, a signal element moved by the oscillatory element, a drive shaft extending longitudinally of the support and connected with the motor, and means operated by the drive shaft for actuating the oscillatory element.
- 20 8. A portable signal device for roadways, comprising an upstanding support, a motor mounted upon the support, an oscillatory element mounted upon the support, a signal element moved by the oscillatory element, and 25 driving connecting means between the motor and the oscillatory element including an eccentric and yoke which have their axes of movements disposed at approximately a right angle.
- 30 40 In testimony whereof, I affix my signature.
